UNITED STATES PATENT OFFICE.

HOWARD E. DAVIS, OF LOS ANGELES, CALIFORNIA.

STYLUS-BAR MOUNTING.

1,413,461.

Specification of Letters Patent. Patented Apr. 18, 1922.

Application filed August 25, 1920. Serial No. 405,801.

To all whom it may concern:

Be it known that I, HOWARD E. DAVIS, a citizen of the United States, residing at Los Angeles, in the county of Los Angeles and 5 State of California, have invented new and useful Improvements in Stylus-Bar Mountings, of which the following is a specification.

It is the object of the present invention 10 to provide an improved mounting for the stylus of a sound reproducing machine, said mounting forming a spring support for the stylus bar and means for accurately adjusting the position of the stylus bar with 15 relation to the sound box and diaphragm for adjusting the spring tension of its support.

The invention will be readily understood 20 from the following description of the accompanying drawings, in which—

Figure 1 is a front elevation of the sound box and stylus bar for a sound reproducing machine.

Fig. 2 is a bottom plan view of the same. 25 Fig. 3 is a detail section on the line 3—3 of Fig. 1.

Fig. 4 is a similar section on the line 4—4 of Fig. 1.

The sound box upon which the improved 30 stylus mounting is provided may be of any usual construction including casing 1 having the diaphragm 2 mounted therein.

The mounting for the stylus bar consists 35 of lugs 3 depending from the sound box in circumferentially spaced relation, said lugs being provided with alined half bearings 4. The stylus bar is shown at 5 secured at one end 6 to diaphragm 2 in usual manner. The opposite end of the stylus bar consists of 40 a usual sleeve 7 having a bore 8 arranged to engage the usual stylus 9. The stylus may be retained within bore 8 by means of a set screw 10.

The stylus bar intermediate of its ends 45 is adjustably mounted with relation to lugs 3, the said adjustable mounting including a spring support for the stylus bar. As an instance of this arrangement a leaf spring extends laterally from opposite sides of the 50 stylus bar and terminates in bearing lugs 13 arranged to be received in the respective half bearings 4.

The leaf spring consists of plates 12 and 55 12' angularly disposed with relation to one another as clearly shown in Fig. 3. By this arrangement a spring mounting for the

stylus bar is provided which will yield in cross directions, to permit of the necessary yield of the stylus bar with relation to its mounting. The movement imparted to the stylus bar by the sound reproducing disc is thus transmitted to the diaphragm 2.

The spring support for the stylus bar is held in position relative to lugs 3 by means of mechanism adapted to accurately adjust 65 bearing lugs 13 within bearings 4 so as to properly position the stylus bar and adjust the tension of its supporting spring. As an instance of this arrangement flanges 15 project from opposite sides of bearing lugs 13 70 in spaced relation from the lugs 3. These flanges are provided at their ends with slots 16 through which extend set screws 17 having their heads abutting against the walls of the slots. The ends of these set screws 75 are threaded into bores 18 extending through lugs 3.

By the construction as thus set forth it will be seen that by adjusting the pairs of set screws 17 at opposite sides of lugs 13 80 with relation to flanges 15, the spring mounting for the stylus bar will be accurately adjusted.

Various changes may be made without departing from the spirit of the invention as 85 claimed.

What is claimed is:

1. The combination with a stylus bar having a spring support comprising crossed leaf springs projecting from opposite sides of 90 said stylus bar.

2. The combination with a sound box having bearings of a stylus bar having a spring support, said support including bearing lugs received in said bearings, and radial wings 95 extending from said support between said bearings and means for adjustably positioning said bearing lugs in said bearings.

3. In a sound box, a stylus bar, a torsional spring passing therethrough, said spring having a plurality of wings radially extending from the longitudinal axis thereof, and means for supporting the outer ends of said torsional spring. 100

4. The combination with a stylus bar of a torsional spring extending from the same, said spring having radially extending wings, and means for mounting the ends of said spring. 105

In testimony whereof I have signed my 110 name to this specification.

HOWARD E. DAVIS.
